THEATER CONSTRUCTION

Max Eduard Liehburg, Basle, Switzerland

Application July 16, 1938, Serial No. 219,624

In Switzerland July 17, 1937

3 Claims. (Cl. 20—1.12)

The theater design or construction according to the invention has at least two main stages without curtains located one behind the other, arranged at a different level and simultaneously and continuously visible by an audience in seats on the audience floor, the ends of the main stages being formed as extensions which run in the form of galleries at least partially around the audience floor and consequently at least partially encompass the audience floor. The extensions in the form of galleries of the different stages are at different levels.

By the arrangement of at least two simultaneously visible stages, which are at different levels and which have lateral projections extending partially or wholly around the auditorium, new possibilities for the theater are given; for, corresponding to the number of stages, much stage surface is simultaneously available for the acting, and lateral stage projections of a gallery nature are available for the development of the acting and thus permits of shifting the stage action over and around the auditorium.

An example of carrying out the invention is shown on the accompanying drawings, in which

Figure 1 is a horizontal section through the ground floor,

Figure 2 is a horizontal section through the upper floor,

Figure 3 is a vertical longitudinal section, and

Figure 4 is a vertical cross-section through the construction,

Figure 5 is a partial representation in perspective seen from the auditorium, and

Figure 6 is an illustration looking from the auditorium towards the stages and their lateral extensions.

1 indicates the auditorium, the audience floor of which is provided with rows of seats 2 which rise stepwise backwardly. In Figure 5 the rows 2 are not shown. The front rows of seats are arranged in the immediate vicinity of a stage surface 3 formed by a circular platform. In Figures 1-3, 4 indicates a vertical wall the lower part of which is cylindrical and limits the audience floor of the auditorium in the main towards the outside. The auditorium wall 4 has entrances 5 (Figure 1) and in the region of the stages 6 and 7, provided in the vicinity of the stage part 3, is interrupted over a certain length of arc in order to leave the audience a free view of the stages 6 and 7. Directly behind the circular stage surface 3 arranged eccentrically to the auditorium 1, is located the raised arc-shaped stage 6 (Figures 3-5) and further behind and still higher is

the arc-shaped stage 7. 8 indicates two sets of chorus seats arranged in the auditorium 1 to the left and right of and in front of the foremost stage 6; these two sets of chorus seats 8 to a certain extent lengthen the rows of seats 2 of the audience laterally and towards the front so that the audience is in close proximity to the choruses. Two stairways 11 connect an outer gangway 9 provided along the outside wall 4 with an inner gangway 10 located eccentrically thereto. The two gangways 9 and 10 merge into the stage surface 3 and serve both as means of access to the rows of seats, and also in particular as acting space or stage.

15 The stages 6 and 7 and the acting surface 3 are arranged in the longitudinal central plane I—I (Figures 1, 2, of the building). The ends 4' of the lower part of the circumferential wall 4 extend up to the front marginal ends of the stage 6. Walls 12 connect on to the ends of the stage 7, that is, on to the other front edge. At the side away from the audience floor, the stage 7 is shut off by a rear wall 13.

Above the gangway 9 there is a wide, horizontal gallery 14, according to Figure 3, which at its ends between the wall ends 4' and the walls 12 is connected by steps 15 with the ends of the stage 6. This gallery 14 which is to be used as a stage by the actors in the same way and in general also simultaneously with the stage 6, and which directly communicates with the said stage 6, is provided with the same coulisses as this stage 6, so that it appears to the spectators as a raised part or extension of the stage 6, and actually does represent an additional part of the stage 6. Above the gallery 14 is a wider horizontal gallery 16 according to Figure 3. This is connected at its ends between the walls 12 and the rear stage wall 13, by steps 17 (Figures 1, 2) with the ends of the stage 7, and is fitted up in the same way as the stage 7, so that the gallery 16 represents both for the audience and also for the actors, a projection of the stage 7. The two galleries 14 and 16 form so-called horizontal stages 45 located above the auditorium. The gallery 16 is, according to Figure 2, considerably wider over a large part of its length than the gallery 14 located below it, so that it correspondingly projects in the direction towards the audience floor. 50 18 (Figures 2, 3) indicates a dancing and gymnastic hall, 19 (Figures 1, 3) is a stage foundation provided behind the stage 7, and 20 and 21 are foyers located one above the other.

The gangways 9 and 10 are, as already mentioned, allocated for acting purposes to the act-

ing surface 3, and can be regarded together with this as a stage which is placed in and around the auditorium. The stage halves and thus the parts of the gangways 9, 10 and the galleries 14 and 16 are located symmetrically to the longitudinal central plane I—I of the theater buildings. The acting surface 3, the gangway 10, and the front part of the rows of seats enclosed thereby are on a circular platform 22. From the acting surface 3 and from the arc-shaped stages 6 and 7, the actors can pass into the gangway 9 or into the galleries 14 and 16 allocated to the corresponding stages and speak parts from there, so that the audience is quite in the center of what takes place. The arrangement of a plurality of stages which are at different levels from each other, with their gallery-like projections running around and which are freely visible from the auditorium and naturally can be used as required for acting purposes, give to the audience the impression of being surrounded by stages. The surrounding wall of the auditorium serves at the same time as side scene or wings wall, so that the audience is seated in the center of what is taking place.

In Figure 5 a few actors are shown by way of illustration on the acting space 3 and also on the stage 6 and on the gallery 14 extending therefrom to the right and left thereof, and in Figures 6 others are shown on the higher stage (7) and on the gallery (16) connecting at the left and right to stage 7. Figure 6 gives a view from the rear of the audience floor toward the stages and their respective lateral extensions. It can be seen from this that the wings of each stage project into the lateral extensions outwardly of the audience floor, and each represents a unit or complete world. By the style of its wings, for example, by Grecian buildings on one stage and Egyptian buildings on the other, or by the color of the stage lighting and the like, each stage can be sharply separated, with its lateral extension, from the other stage. Each stage can symbolise by its decoration and by the acting which takes place on it, a separate world. Thus for example, the first stage can represent the present, the second stage the historical world, and the third the mythological or cosmos. Representations completely independent of each other which for example take place in different regions and at the same or different periods, can be shown on the different stages. The actions on the one stage can also be brought into connection with the acting on the other stages.

The circular acting surface 3 and also the arc-shaped stages 6 and 7 are arranged so that they can be lowered. The stage 7 can, for example, be so lowered that its upper side comes flush with that of the stage 6, whereby the surface of the latter is correspondingly enlarged. The projections in the form of galleries of the stages can if desired only extend over a part of the space around the auditorium.

As can be seen from Figures 3 and 4, the ceiling 23 of the building covering the whole of the stages forms a level uninterrupted surface which is curved all around downward at the edge. This form of ceiling is very advantageous for the production of light effects and there can be projected thereon all sky effects, whilst it is also favorable for sound reflection when, for example, speaking takes place from the topmost gallery 16.

I claim:

1. A theater comprising an auditorium having a floor; a first portion of said floor being provided with seats for an audience; a plurality of stepped, arcuate, curtainless main stages at successively higher levels in the direction away from said seats; said main stages being in front of said seats so as to be simultaneously and constantly visible by an audience in said seats; a second portion of the floor adjacent the lowest of said main stages and in front of said seats being free of seats and reserved for acting; a third portion of said floor extending from the second portion thereof among the seats also being free of seats and reserved for acting; a fourth portion of said floor, at the periphery of the portion provided with seats, being free of seats and reserved for acting, steps connecting the third and fourth portions of said floor, said main stages being provided at their lateral ends with extensions forming gallery-like stages which lie at different heights with respect to each other and with respect to their respective main stages and extend at least partially around the audience floor and thus encompass it, and walls extending upwardly at the sides of the main stages to the front part of the respective gallery-like stages.
2. A theater comprising an auditorium having a floor; a portion of said floor being provided with rows of seats for an audience; a plurality of stepped, arcuate, curtainless main stages at successively higher levels in the direction away from said seats; said main stages being in front of said seats so as to be simultaneously and constantly visible by an audience in said seats, said main stages being provided at their lateral ends with extensions forming gallery-like stages which lie at different heights with respect to each other and with respect to their respective main stages and extend at least partially around the audience floor and thus encompass it, walls extending upwardly at the sides of the main stages to the front part of the respective gallery-like stages, and rows of chorus seats at both sides and in front of the foremost of said stepped stages, said chorus seats prolonging the audience seat rows laterally and forwardly.
3. A theater comprising an auditorium having a floor having a portion reserved for an audience and provided with rows of seats, a plurality of stepped, arcuate, curtainless main stages being simultaneously and constantly visible by an audience in said seats, said main stages being provided at their lateral ends with extensions forming gallery-like stages which extend above the audience floor at different heights with respect to each other and also with respect to their respective main stages at least partially around the audience floor and thus encompass it, steps connecting said gallery-like stages with their respective main stages, the uppermost of said gallery-like stages extending inwardly in the direction of the audience floor beyond the lower gallery-like stage, the gallery-like stage more remote from the audience floor being at a higher level than the gallery-like stage closer to the audience floor, and walls extending upwardly at the sides of the main stages to the front part of the respective gallery-like stages.
